UNITED STATES PATENT OFFICE.

CHRISTIAN BODMER, OF NEW BRITAIN, CONNECTICUT, ASSIGNOR TO THE STANLEY RULE & LEVEL COMPANY, OF NEW BRITAIN, CONNECTICUT, A CORPORATION OF CONNECTICUT.

DESIGN FOR A SAW-SET.

50,055.

Specification for Design.

Patented Dec. 19, 1916.

Application filed June 13, 1916. Serial No. 103,583. Term of patent 14 years.

To all whom it may concern:

Be it known that I, CHRISTIAN BODMER, a citizen of the United States, residing at New Britain, county of Hartford, State of Connecticut, have invented a new, original, and ornamental Design for a Saw-Set, of which the following is a specification, reference being had to the accompanying drawing, forming a part thereof, in which—

Figure 1 is a side elevation of a saw set

illustrating my new design. Fig. 2 is a plan view.

I claim:

The ornamental design for a saw set as shown.

CHRISTIAN BODMER.

Witnesses:

WILLIAM A. BODWELL,
H. E. PARKER.
